UNITED STATES PATENT OFFICE.

JOEL C. WELLS, OF SOUTHBRIDGE, MASSACHUSETTS.

EYEGLASSES.

1,158,605.

Specification of Letters Patent.

Patented Nov. 2, 1915.

Application filed May 31, 1913. Serial No. 771,026.

To all whom it may concern:

Be it known that I, JOEL C. WELLS, a citizen of the United States, residing at Southbridge, in the county of Worcester and State 5 of Massachusetts, have invented certain new and useful Improvements in Eyeglasses, of which the following is a specification.

My invention relates to improvements in spectacles and has particular reference to 10 improved means for retaining in position on the face a structure of this character embodying a rigid as contradistinguished from a spring bridge.

The leading object of my invention is the 15 provision of novel and improved means for securing a rigid bridge spectacle mounting in position on the face of the wearer.

A further object of my invention is the provision of a mounting which shall, in addition to embodying my improved securing means, be constructed to afford maximum adjustability whereby a single size of mounting can be adapted to the requirements of a variety of different facial characteristics and 25 measurements.

Other objects and advantages of my improved construction should be readily apparent by reference to the following description taken in connection with the accompanying drawings, and it will be understood 30 that I may make any modifications in the specific details of construction hereinafter shown and specifically described within the scope of the appended claims without departing from or exceeding the spirit of my invention.

Figure I represents a front view of a pair of glasses constructed in accordance with and embodying the principle of my invention. Fig. II represents a top plan view thereof. Fig. III represents a fragmentary front elevation of a slight modification of my invention. Fig. IV represents a face view of the guard and other parts as illustrated in Fig. III. Fig. V represents a fragmentary front view of another modification of my invention parts being shown in section. Fig. VI represents a top plan view thereof. Fig. VII represents an enlarged 45 detail view, particularly illustrating the construction of guard and operating means therefor. Fig. VIII represents a plan view of another form of my invention. Fig. IX represents a plan view of a slight variation 50 of Fig. VIII. Fig. X represents a detail

view of one form of my guard such as shown in Fig. II. Fig. XI represents a plan view of the blank for forming the guard shown in Fig. IV. Fig. XIII represents a detail view of another modified construction of 60 guard. Fig. XIII represents a fragmentary slightly perspective view illustrating another form of my invention constructed to afford a wide range of adjustability. Fig. XIV is a view similar to Fig. XIII of a slightly different construction. Fig. XV is a perspective view of the structure shown in Fig. XIV. Fig. XVI represents a slight modification thereof. Fig. XVII represents an enlarged detail view of the pad supporting 70 member. Fig. XVIII represents a fragmentary perspective view illustrating another modified form of pad and actuating means therefor. Fig. XIX is a view of another modification. Fig. XX represents a 75 slight modification of the construction illustrated in Figs. V, VI and VII. Fig. XXI represents another modification of bearing members. Fig. XXII represents a further modification thereof. Fig. XXIII represents a plan view of the blank from which the structure shown in Fig. XXII is formed. Fig. XXIV represents a perspective view 80 illustrating a modified means for manually operating the gripping pads. Fig. XXV represents a similar view of a slightly different arrangement of said pad controlling means.

In the drawings, in which similar characters of reference are employed to denote 90 corresponding parts throughout the several views, the numeral 1 designates the lenses having secured thereto the usual lens attachments 2 connected by a bridge member 3. In certain of the forms of my invention I 95 have shown the bridge as connected direct to the lens attachment 2, while in other forms I have shown the bridge connected to the lens attachment through the medium of a stud box 4 of ordinary construction. It 100 will be noted that in all of the forms of my invention I employ a lower weight bearing guard in combination with an upper suitably actuated moving gripping member which has a very limited range of movement, the said upper member serving to anchor the glasses in position, as hereinafter more fully set forth.

In that form of my invention shown in Figs. I and II, I employ the lower weight 110

supporting portion 5 having secured thereto as by riveting, the spring loop 6 bearing the anchoring pad 7 and the said loop terminating in a slotted portion 8 extended outwardly from the pad. To control the position of the pad 7 I pivot or suitably fulcrum on the bridge the levers 9 having the handle portions 10 and having their inner ends engaged in the slots of the portions 8 of the spring loop whereby grasping and pressing together of the handles 10 will tighten the loops 6 and throw the pads 7 outward out of engagement with the nose, the adjustment of the spring loops being such that the pads 7 are normally disposed inward at an angle to the supporting members 5, as is clearly shown in the plan views, the front edges thus biting into the loose skin at the top of the nose to retain the mounting in place.

In that form of my invention illustrated in Figs. III and IV, the levers are pivoted to swing in a vertical instead of a horizontal position and have on their inner ends the lugs 11 engaging suitable tongues 12 on the pads 7, the spring loop as shown being integral with the pads 7 and weight supporting member 5 instead of riveted or otherwise secured thereto as in the previously described form of guard. It is to be noted that in this form of my invention the arm 27 carrying the weight supporting member 5 and the pad or gripping member support, has a loop formed therein to afford maximum adjustability, the terminus of said loop being attached to the arched portion 3 of the bridge, while the bridge exterior to said arched portion has the loop 3' formed therein between the arch and the lenses to permit of ready adjustment of the lenses relative to the bridge and guards or nose bearing portions.

In Figs. V, VI and VII, I have illustrated a modification of my invention as used in conjunction with a stud box mounting, but it will be understood that the stud box may be eliminated if desired and the various parts integrally formed or secured together. In this form of my invention the weight supporting pad 5 has the arm 13 for engagement in the stud box and has extending upwardly therefrom a pintle 14 on which is pivotally mounted a pad 7 having curled portions or ears 15 engaging the pintle, while disposed between said ears is an actuating spring 16 tending to turn the pad 7 inward on the pintle as a pivot. To enable one to readily move the pad 7 out of engaging position, I provide each pad with a flange or flanges 17, each having a slot 18 formed therein to receive a pin 19 on the end of the operating lever 9. The lever 9 instead of being fulcrumed on the bridge is slideable on the box or guide 20. A slight modification of this construction is illus-

trated in Fig. XX, this form being adapted for use in conjunction with a stud box and bracket 20, as just described, the pad, however, being supported by a resilient loop 6 instead of pivoted on the pintle 19, and having curving downward from its upper edge the loop 31 bearing the slotted member 17, in which rides the pin 19 on the lever.

In the use of these forms of my invention the handles 10 are grasped preferably by the thumb and second finger of the hand, while the first finger is placed against the bridge. The handles 10 are then drawn directly forward, the pins 19 riding in the slots 18 and as said slots are normally at an angle to the direction of movement of the levers this forward drawing of the handles 10 will open out the pads 7, as should be readily apparent by reference to Figs. VI and VII.

In Fig. VIII, I have shown another slight modification of my invention in which the pads 7 are rotatably mounted on the pintles 14 and have extending laterally substantially parallel to the lenses the portions 21 connected by means of springs 22 to the lens attachments 2. In this form of my invention I slidably connect to the bridge the U-shaped member 23 having the inwardly extending arm portions 24 adapted to contact with the portions 21 of the pads, inward movement of the U member relative to the bridge swinging the pads to release the same thereof from gripping position against the tension of the springs 22. In the use of this form of my invention the glasses may either be held by the thumb and fingers with one finger bearing against the member 23, or I may provide the stationary handles 25 suitably secured to the mounting for grasping by the thumb and second finger, while the first finger presses against the base of the U member.

In Fig. IX, I have illustrated a mounting similar to that in Fig. VIII with the exception that the pads are not provided with the extensions 21 but are actuated by the U member itself which is made of spring material and so mounted as to ordinarily actuate the pads inwardly but to spread on pressure against the central portion thereof to relieve the pads of pressure and tend to draw the same outward into disengaging position.

In Fig. XII, I have shown a form of guard adapted for use in conjunction with several of the modifications of actuating means above illustrated; in this instance the pad 7 instead of being pivoted on the pintle 14 is carried by the coil spring member 26 which is secured to said pintle, the tension of the spring tending to throw the front edge of the pad inward and a suitable releasing means being provided to throw this front edge into disengaging position.

Fig. XIII is another form of my inven-

tion in which the same means serve to transmit motion to the pad in both directions, in this form the bridge 3 having the looped adjustable portion 3' and having secured there-
5 to the looped arm 27 carrying the weight supporting guard member 5 and the gripping member 7, which is pivotally mounted on the spindle 14. A pivot rising from the bridge 3 supports the lever 9, while disposed
10 above the lever is a spring 28 bearing at one end against the lever and at the other against the mounting to swing the lever inwardly and push the pad into operative position, grasping of the handle portion of the
15 lever serving to withdraw the pad from operative position.

In that form of my invention shown in Figs. XIV to XVII inclusive, I have entirely dispensed with any manual operating
20 means for the pad and in these forms I have shown the pad as rotatably supported on the spindle 14 and actuated by the spring 30 retained in the cup 29 but it will be understood that other forms of my pads as shown in the
25 various views may be employed without the manually controlling means therefor, in the same manner as that shown in the above mentioned figures.

Fig. XVIII represents a further modification of my invention in which the pad 7 turns on the spindle 14 and is actuated by the spring loop 6' extending upward from the lower portion of the bearing member 5, the lever 9 engaging an eye on the end of
35 the said spring arm or loop 6' to permit of outward movement of the front edge of the pad 7.

The form of my invention illustrated in Fig. XIX is similar to several of the previously described views, with the exception that the lever 9 engages the pad at the bottom thereof instead of at the top or forward portion thereof, the lever in this instance, as in the others, shifting the pad out of
45 gripping position.

Fig. XXI differs from my other forms merely in having the loop 31 coming downward from the top thereof instead of from the forward edge or back of the pad.

Figs. XXII and XXIII illustrate a slight modification in that the main guard member has formed thereon the pair of ears 33 bent to form bearings for the spindle 34 of the pad 7, and in addition there is integral with
55 the main guard member the loop 6, which is riveted to the forward portion of the pad 7 and has projecting from the sides thereof the ears 32 for engagement by the furcated end of the lever 9 to properly shift the pad
60 7 into inoperative position.

In Figs. XXIV and XXV, I have shown one of my regular types of guards with the perforated ears 8 extending from the back of the pad portions 7, which are actuated by
65 the spring loops 6, while I have shown the

bridge as slotted or apertured to receive the sliding bars 35 having hook portions 36 engaging the ears 8 and having the usual handle or finger engaging portions 10 to facilitate sliding of the bars to open up the pads, 70 as should be readily apparent by reference to the drawings.

From the foregoing description the operation of my improved construction should be readily apparent, and it will be seen that 75 I have provided an improved type of mounting embodying lower weight supporting pads, upper pads suitably actuated for gripping or biting into the loose flesh on the upper part of the nose of the wearer and actuating means preferably independent of the supports for the pads for throwing the same into operating position and for shifting the pads out of operative position. It will further be observed that I have provided an 80 improved construction of spectacle mounting embodying an entirely new and novel method of operation, in that I provide a bridge or connecting member to fit around or in engagement with the bridge of the nose 85 of the wearer and support by said connecting member, weight supporting pads adapted to rest on the sides of the nose of the wearer, which pads are mounted for adjustment to actually bear upon and fit the nose 90 and support the weight of the mounting and practically balance the mounting on the nose, while in addition to these lower substantially rigid bearing portions, I have provided gripping members so disposed as 100 to grip or bite into the loose flesh at the top of the nose and resist tilting of the mounting on the weight supporting guards as a fulcrum, the entire function of these latter members 7 being to grip and resist this tilting of the mounting and the same being preferably mounted to swing about an axis posterior to the anterior edge thereof so that said anterior or front edge may swing in to 105 bite into the flesh and will more firmly engage said flesh and grip the same in the manner of a hook upon any forward tilting of the mounting, although other forms of pads than those having such a hook action may be employed if desired. It will thus be 110 seen that my mounting can readily be placed in the face by raising the weight supporting portions in correct position and slightly pressing the mounting inward, when the pads 7 will readily yield and will allow the 115 nose to force itself therebetween without any undue pressure, and at the same time the resilient actuating means for said pads will cause them to satisfactorily grip the nose and prevent accidental forward or dropping 120 off movement of the glasses.

While in a number of figures I have illustrated manual means for releasing the pads, it is to be understood that I do not wish to be limited to a structure in which manual 136

means for disengaging the pad from the nose are employed, these being provided merely for the convenience of persons not fully understanding the operation of the mounting and to facilitate the removal thereof, since persons skilled or properly instructed in the manner of wearing my improved mounting can readily remove the same without the use of these manually controlled means for operating the pads and at the same time without scratching or bruising the nose.

I claim:

1. In an eyeglass mounting, the combination with a rigid bridge shaped to the curve of the nose of depending guard members held in fixed relation to the bridge, upwardly and rearwardly extending, pad supports carried by one of the first named parts, and gripping pads mounted on the supports for movement about axes posterior to the anterior edge thereof, said pads being normally disposed with their front edges inwardly of their rear edges and at a greater angle than that of the surface of the nose intended to be engaged thereby, whereby the mounting may be slipped rearwardly on the nose, and the nose will readily slide between the pads while their front edges will bite inward into the nose to resist accidental disengagement of the mounting therefrom, substantially as described.

2. In a mounting of the character described, the combination with a rigid bridge adapted to fit the nose of the wearer, a pliable arm supported by each end of the bridge, and extending rearwardly therefrom, said arm being rigidly connected to the bridge, and a pair of nose engaging members supported by each of the pliable arms, said members comprising a lower rest, a post rising above the rest, and a gripping member on the post mounted for movement about an axis posterior to the anterior edge thereof, said gripping member being disposed at an acute angle to the plane of the lower member, whereby when the lower member is adjusted to fit the side of the nose the upper member will be faced inward at an angle thereto to bite into the side nose and prevent accidental disengagement of the mounting therefrom.

3. The combination with a bridge and lens supports, of weight bearing pads carried thereby, free front edge gripping pads, means for forcing said free front edges into gripping position, and independent manually operable means for shifting said front edges into inoperative position.

4. An eyeglass mounting including gripping members supported posterior to the anterior edge thereof for swinging movement about a vertical axis, means for actuating the gripping members in one direction

and additional means for swinging the gripping members in the opposite direction.

65

5. In an eyeglass mounting, the combination with lens supports, of weight supporting members carried thereby gripping members, means for swinging the gripping members into biting engagement with the nose of the wearer, and independent manually operable means for swinging the gripping members into inoperative position.

6. The combination with lens supports, of weight carrying members secured thereto, gripping members mounted for swinging movement on an axis rearwardly of the forward portion thereof and separate means for inwardly and for outwardly actuating the gripping members.

7. In an eyeglass mounting, the combination with an eyeglass guard embodying a stationary lower portion and an upper portion movable relative thereto about a vertical axis, resilient means for actuating the pad in one direction and independent manually operable means for operating the pad in the opposite direction.

8. An eyeglass mounting including a guard having a stationary lower portion and an automatically relatively movable upper portion, and manual means for moving the front edge of the upper portion outward.

9. In an eyeglass mounting, the combination with a support for the lenses, of a gripping member mounted to turn about an upright axis located rearwardly of the front edge of the gripping member, and means for forcing the front edge of the gripping member inward and additional means for shifting said front edge outward.

10. In an eyeglass mounting, the combination with a support for the lenses, of a gripping member mounted to turn about an upright axis disposed rearwardly of the front edge of the gripping member, resilient means for automatically turning the gripping member about said axis whereby the front edge of the gripping member is forced inwardly, and manually operable means for forcing said front edge outwardly.

11. A spectacle mounting embodying a support, a lower guard member carried thereby and adjustable relative thereto, a displaceable upper gripping member carried by one of said parts and movable relative to both of the first mentioned parts, means for shifting said upper member inwardly, and additional means for outwardly shifting said member to render the same inoperative.

In testimony whereof I affix my signature in presence of two witnesses.

JOEL C. WELLS.
